UNITED STATES PATENT OFFICE.

ALBERT BRYAN McCAIN, OF REWARD, CALIFORNIA.

GRIP CAGE GRAB FOR DEEP-WELL PUMPS.

Application filed January 24, 1928. Serial No. 249,031.

This invention relates to a general class of devices known as well fishing tools.

It has for its object to provide a positive grip cage grab, which may be lowered into a well for the recovery of lost objects, means being included in the tool for automatically operating a plurality of grab hooks so that when the tool contacts with the object the hooks or prongs will be moved into an engaging position.

It is well known in the oil industry that one of the principal processes of inducing production from oil wells is to introduce a pump therein, which consists of a working barrel attached to a string of tubing, lowered into the well to a depth below the oil level. Within this working barrel there is the usual plunger device used in this form of pump and at the head thereof is the working valve, consisting of a cage with three openings spaced equidistant, within which cage there is a hardened ball, accurately engaging the valve seat. This working valve is attached to a string of sucker rods by a short threaded stem engaging the lower end of the sucker rod.

One of the most frequent accidents that occur to this pumping device in its operation is the breaking or snapping off of this short engaging stem, which necessitates the pulling of the sucker rod, and upon the failure of the ordinary fishing devices now known it is necessary to undertake the costly and arduous operation of disengaging and pulling the entire string of oil pumping tubing. The ordinary cage spear now known to the industry is uncertain in its operation and seldom successfully engages the pumping cage because of the lack of guidance. This uncertainty in fishing operations; together with the costly resultant operation of pulling the tubing where it fails, is entirely eliminated by the device which is the subject of this invention.

It is therefore a further object of this invention to provide a tool of the character described which by reason of its design and construction is particularly adapted to recover the cage heretofore referred to in the use of deep well pumps.

With the above and other objects in view, the invention further includes the following novel features and details of constructions, which are hereinafter more fully described and illustrated in the accompanying drawing.

In the drawing:

Fig. 1 is a vertical sectional view of a grip cage grab constructed in accordance with this

invention, one of the prongs being shown partly in sections.

Fig. 2 is a bottom view of the tool.

Fig. 3 is a view similar to Fig. 1, showing the prongs released and the grabs in an engaging position.

Referring now more particularly to the accompanying drawing in which like numerals designate like parts throughout the several views, the numeral 4 designates the hollow cylindrical casing which is open at the bottom and into which a pull rod 5 is removably suspended on the screw threaded connection 6. The pull rod has a protruding head 7 on which rests the internal shoulders 8 of the prongs 9 and which are also within the casing 4. Prongs 9 are provided with grabs 10 which are adapted to move within the recesses 11 so that when in operative position as shown in Fig. 1, the exterior surface of the prongs 9 are flush with the outside of the casing 4. Grabs 10 are also provided with tapering interior surfaces which enables them to slide over the cage when it is encountered.

On the pull rod 5 there is provided a locking block 12 provided with a recess 13 in its bottom which is adapted to receive the top portions 14 of the prongs 9. Attached to the locking block 12 by a threaded connection 15 is a trip rod 16, which upon striking the object or cage is utilized to raise the locking block against the action of the coil spring 17 which encircles the pull rod 5. When the locking block 12 is raised the upper part of the prongs 9 are forced outwardly by the action of the resilient fingers 18 connected to the prongs 9 at the shoulder portions 8 and slidably bearing against the pull rod 5. The device then assumes the position shown in Fig. 3.

This device is particularly adapted to grip a pump cage which has been omitted from Fig. 3 in order that the working parts of the invention may be more clearly shown. The working cage of the pump is a triangular object having shoulders which will be received in the recesses 19 of the casing, and between these shoulders there are three openings, into which the grabs 10 will spring when the trip rod 16 has encountered the cage.

In order to set this device for further use, pressure should be exerted on pull rod 16 to raise the locking block 12, and the part 14 of the prongs 9 are pushed inwardly against the pull rod through the holes 20 releasing the pressure on the trip rod and thereby allow-

ing the locking block to regain its position and retain the prongs.

The particular feature of this device which renders its action certain and unerring is the fact that its external diameter fits the internal diameter of the tubing, and the length of the casing 4 in which the device is enclosed, centers the gripping prongs so that they are held in position and slide over the head of the 10 working cage of the pump, which is also held rigidly in place by the pumping barrel. When the gripping prongs are released, they unfailingly engage the cage, and no other fishing device that is used in pumping tubing 15 is known to embrace this feature.

This same device may be used in pulling a sanded pump, where the standing valve is rendered inoperative, by the use of a left-handed thread on the lower coupling of the 20 sucker rods, disengaging such rods and applying the grab as heretofore described. This method of procedure does away with annoyance, cost and loss of time and oil in what in the trade is known as a "wet job" in pulling tubing. This device may also be further used in the same manner with like effect in the 25 event the garbutt rod, which is attached to the lower standing valve or cage of the pump becomes broken or disconnected. In this case, the working barrel is withdrawn from the 30 well along with a string of sucker rods and the device lowered into place, tripped and attached on the lower valve or cage in the same manner as before.

35 Having now more particularly described the preferred form of this invention, what is claimed as new is:

1. A grip cage grab consisting of a hollow casing open at one end, a pull rod removably 40 suspended within the casing, said pull rod being provided with a protruding head, gripping prongs having shoulders resting on the protruding head of the pull rod, a locking block slidable upon the pull rod and adapted

to engage the prongs, and means for raising 45 the locking block to release the gripping prongs.

2. A grip cage grab consisting of a hollow casing open at one end, a pull rod removably 50 suspended within the casing, said pull rod being provided with a protruding head, gripping prongs having shoulders resting on said protruding head of the pull rod, a locking block slidable on the pull rod and adapted to engage the prongs, a means engaging the locking block to hold it in operative position and means for raising the locking block to release the gripping prongs.

3. A grip cage grab consisting of a hollow 60 casing open at one end, a pull rod removably suspended within the casing, said pull rod being provided with a protruding head, gripping prongs having shoulders resting on said protruding head of the pull rod, a locking block slidable over the pull rod and adapted to engage the prongs, a spring encircling the pull rod and maintaining the locking block in operative position, a trip rod extending below the casing and connected to the locking block, said trip rod adapted to raise said locking block upon contacting with an object, and means for forcing said gripping prongs into an engaging position.

4. A grip cage grab consisting of a hollow 75 casing open at one end, a pull rod removably suspended within the casing, said pull rod being provided with a protruding head, gripping prongs having shoulders resting on said protruding head of the pull rod, a locking block having a recess in the bottom and slidable on the pull rod, said recess being adapted 80 to receive the top of the prongs and maintain them in inoperative position, means for raising the locking block to release the gripping prongs and means for forcing the gripping prongs into an engaging position.

ALBERT BRYAN McCAIN.
